FLUID PRESSURE DEVICE

John C. Cotner, Logansport, Ind., assignor to
 Logansport Machine, Inc., Logansport, Ind.,
 a corporation of Indiana

Application March 14, 1936, Serial No. 68,898

7 Claims. (Cl. 137—153)

My invention relates in general to fluid pressure devices, and more particularly to fluid devices for maintaining the fluid pressure in a fluid system at a substantially uniform pre-determined value.

An object of my invention is the provision of a fluid pressure device actuated by the pressure of the fluid being controlled and maintaining the pressure of the fluid being controlled at a substantially pre-determined value.

Another object of my invention is the provision of a fluid pressure device having a major valve for controlling the pressure of the fluid and a pilot valve influenced by the pressure of the fluid for controlling the operation of the major valve.

A still further object of my invention is the provision of a balanced major valve for controlling the pressure of a fluid, together with means for actuating the movements of the balanced major valve by by-passing a portion of the fluid to establish oppositely disposed fluid pressures upon the balanced major valve and by providing escapement means for the by-pass fluid which determines the movements of the balanced major valve.

Another object of my invention is the provision of a balanced major valve and a pilot valve for controlling the balanced condition of the major valve, together with cushioning means cooperatively associated with the pilot valve for insuring smooth operation of the pilot valve, as well as for the balanced major valve.

Another object of my invention is the provision of a balanced major valve and a slide valve as a unit slidable with reference to each other and mounted in a cylinder to provide a good compact assembly.

A still further object of my invention is the provision of a fluid pressure device which may be utilized as a line pressure maintaining device or as a relief valve.

A still further object of my invention is to provide a design wherein the air in the oil or other liquid fluid being controlled is allowed to escape.

A still further object of my invention is the provision of a fluid pressure device of such design that the variations in the fluid pressure are reduced to a very low minimum.

Other objects and a fuller understanding of my invention may be had by referring to the following description and claims, taken in conjunction with the accompanying drawing, in which:

Figure 1 is a cross-sectional view of a form of

my invention and shows the balanced major valve and the pilot valve as being constructed in a unit slidably positioned in the longitudinal central cylinder of the body of the fluid device and is illustrated as a pressure relief valve; and

Figure 2 is a modified form of the invention shown in Figure 1, in that the valve is illustrated in the form of a poppet valve instead of a slide valve.

In Figure 1, I show a cross-sectional view of a form of my invention and shows the balanced major valve and the pilot valve as being constructed in a unit slidably positioned in a longitudinal central cylinder of the body of the fluid device and is illustrated as a pressure relief valve. 10 This form of my invention comprises generally a body member 72, a major slide valve member 76, a pilot slide valve sleeve 83 surrounding the major slide valve member 76 and an adjustment screw 104 for varying the fluid pressure at which the fluid may pass through the fluid device. 15

The body member 72 has a fluid passage-way 13 and a major longitudinal cylinder 82 extending centrally and vertically of the body member 72. As illustrated, the pilot slide valve sleeve 83 is provided with two oppositely disposed openings 111 and is reciprocally positioned within the major longitudinal cylinder 82. The major slide valve member 76 is reciprocally mounted in the pilot slide valve sleeve 83. Accordingly when the major slide valve member 76 is raised, fluid is allowed to flow from the inlet fluid pipe 74, the fluid passage-way 13, through the opening 111 in the wall of the pilot slide valve sleeve 83, from thence it flows into the fluid passage-way 110 and out through the fluid pipe 75. The major slide valve member 76 is of the differential type 20 and has a fluid stepped area 77 and an oppositely disposed fluid stepped area 78. Therefore, the pressure of the fluid tending to raise the major slide valve member 76 is the differential action 25 of the fluid pressure acting upon the fluid stepped area 77 minus the fluid pressure acting upon the fluid stepped area 78. The lower end of the major slide valve member 76 is provided with a piston portion and is reciprocally mounted within the longitudinal opening 80 provided in the lower end of the body member 72. Below the lowermost end of the major slide valve member 76, there is a fluid cavity 89, which is enclosed 30 by means of a threaded plug 81.

The uppermost part of the major slide valve member 76 is in the form of a piston and is reciprocally mounted within the pilot slide valve sleeve 83.

In order to form a piston chamber 93 above after flowing through the grooves 114 flows out into the fluid passage-way 110, through a duct 115. Also the fluid which may leak past the lowermost end of the major slide valve member 76 into the fluid cavity 89 is allowed to escape 5 to the fluid passage-way 110 by means of the fluid duct 116.

As illustrated, the piston area 79 on top of the major slide valve member 76 is greater than the differential area of the stepped area 77 minus 10 the stepped area 78 which means that under conditions of equal fluid pressures upon these areas, the piston is hydrostatically urged downwardly.

In explaining the operation of my device, let it be assumed that the pressure of the fluid is 15 below the pre-determined setting as determined by the adjustment screw 104. Under this condition, the fluid in the fluid passage-way 13 flows through the restricted by-pass 112 and the restricted orifice 113 into the piston chamber 93. 20 After the piston chamber 93 is full, the pressure of the by-pass fluid in the piston chamber 93 is the same as the pressure in the fluid passage-way 13. Therefore, the hydrostatic force of the fluid in piston chamber 93, acting upon the upper 25 end 79 of the balanced major slide valve member 76, is greater than the differential hydrostatic force of the fluid in the passage-way 13, acting upon the stepped shoulder 77 and 78. This means that the major slide valve member 76 30 under this condition is hydrostatically forced downwardly in its closed position and prevents the fluid within the fluid passage 13 from escaping. Also under this assumed condition, the pilot slide valve sleeve 83 is urged downwardly in its 35 closed position by reason of the fact that the tension of the spring pressure 101 is greater than the hydrostatic pressure of the fluid acting upon the lower peripheral edge 87 of the pilot slide valve sleeve 83. Accordingly the by-passed 40 fluid entrapped in the piston chamber 93 cannot escape.

Now let it be assumed that the pressure of the fluid being controlled exceeds a pre-determined value as set by the adjustment screw 104. Under 45 this condition, the hydrostatic force of the fluid acting upon the lower peripheral edge 87 of the pilot slide valve 83 is greater than the opposing downward force of the adjusting spring 101. As a result, the pilot slide valve sleeve 83 is urged 50 upwardly and the longitudinal grooves 117 interconnect the piston chamber 93 to the exit fluid passage 110 through the fluid duct 115. This means that under the opened condition of the pilot slide valve sleeve 83, the fluid entrapped 55 in the piston chamber 93 flows through the openings 114 in the wall of the pilot slide valve sleeve 83, the grooves 117, the fluid duct 115, the exit fluid passage-way 110 and out into the exit pipe 75. Just as soon as the by-passed fluid entrapped in the piston chamber is allowed to 60 escape, the pressure of the entrapped fluid is materially reduced to the point that the value of the hydrostatic force of the fluid tending to raise the major slide valve member 76 acting differentially against the stepped shoulders 77 and 78, is greater than the hydrostatic force acting 65 downwardly against the top piston area 79 of the major slide valve member 76. This hydrostatically forces the major slide valve member 76 70 upwardly and allows the fluid in the fluid passage-way 13 to flow through the openings 111 in the wall of the pilot slide valve sleeve 83 and into the exit fluid passage-way 110, where the fluid escapes through the exit pipe 75. It is

75

The fluid in the fluid passage-way 13 is allowed to flow through a restricted by-pass 112 that interconnects the stepped shoulder 77 with the top surface of the major slide valve member 76. In order to vary the resistance to the flow of the fluid through the restricted by-pass 112, I utilize a replaceable orifice 113 threadably engaged in the upper portion of the major slide valve member 76. Therefore, the resistance to the flow of the fluid through the restricted by-pass 112 may be selected by means of choosing the proper size of replaceable orifice 113 to accommodate any particular design of a fluid device embodying the features of my invention.

The by-pass fluid entrapped in the piston chamber 93 is allowed to escape to the fluid passage-way 110 and out through the exit pipe 75 when the pilot slide valve sleeve 83 is raised. This escapement is effected by allowing the fluid to flow through oppositely disposed fluid openings 114 into the grooves 117 provided in the external wall of the pilot slide valve sleeve 83. As illustrated, the upper end of the grooves 117 is tapered so as to provide a gradual opening as the pilot slide valve sleeve is raised. The fluid,

5 noted that the resistance offered to the flow of the fluid through the restricted by-pass 112 and the restricted orifice 113 is greater than the resistance offered to the flow of the fluid through the fluid duct which connects the piston chamber 93 in communication with the exit fluid chamber 110. As a result, the fluid in the piston chamber 93 is allowed to escape when the pilot slide valve sleeve 83 is opened, at a faster rate 10 than that which the fluid can flow into the piston chamber 93 through the restricted by-pass 112 and the restricted orifice 113.

15 To give gradual and smooth operation, the upper end of the fluid grooves 117 of the pilot 20 slide valve sleeve 83 is gradually tapered. This means that in the early stages of the opening of the pilot slide valve, the escapement of the fluid from the piston chamber 93 is gradual. Consequently, the upper movement of the major slide 25 valve member 76 is likewise gradual, which in turn, provides a gradual escapement of the fluid from the passage-way 73 into the exit passage-way 110. The gradual escapement of the fluid from the fluid passage-way 73 into the exit passage-way 110 reduces the pressure of the fluid 30 in the passage-way 73 and causes the pilot slide valve sleeve 83 to be again closed, whereupon the major slide valve member 76 moves downwardly and closes the fluid openings 111 in the wall of the pilot slide valve sleeve 83. The cycle of raising and lowering the major slide valve member 76 is gradually repeating itself and in actual 35 operation, the major valve member 76 is balanced and assumes a position corresponding to the position of the pilot slide valve 83.

40 It is noted that in the operation of my device that the major slide valve member 76 does not open until after the pilot slide valve sleeve 83 is raised sufficiently and connects the piston chamber 93 with the exit fluid passage-way 110. By reason of this condition, the variations in the fluid pressure are reduced to a very small minimum.

45 As illustrated, the flange 84 on the upper end 50 of the pilot slide valve sleeve 83 is provided with an opening 124 and the outward flange 94 on the body cylinder cap 92 is likewise provided with an opening 123. This means that whatever fluid escapes between the clearance of the outward 55 flange 84 of the pilot slide valve sleeve 83 and through the clearance around the plungers of the 60 slidable plunger assembly 99 may drain to the exit valve passage-way 110.

65 In this embodiment of my invention, the spring 70 85 constitutes a cushioning device to give a smooth operation to the pilot slide valve sleeve 83.

In Figure 2, I show a modified form of the invention from that shown in Figure 1 in that the differential major slide valve member 76 is replaced by a poppet valve 119 which allows fluid to flow from the fluid passage-way 73 past the major poppet valve 119 and out through the exit pipe 120. The threaded opening in which the exit pipe 15 screws in Figure 1 is plugged with a threaded plug 121. In this modified form of my invention, the fluid in the piston chamber 93 is allowed to escape through the openings 114 in the wall of the pilot slide valve sleeve 83, the grooves 117, and thence out through a fluid duct 75 122 into the exit pipe 120.

The operation of the device shown in Figure 2 is substantially the same as that described with reference to that shown in Figure 1. That is to say, the fluid is allowed to flow when it attains a pre-determined pressure as determined by the

setting of the adjustment screw 104 and prevented from flowing when the pressure falls below the setting of the said pre-determined value.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A fluid pressure device comprising, in combination, a body member, a major valve having a movable member slidably mounted in the body member, said movable valve member having two oppositely disposed fluid portions for hydrostatically actuating the movable valve member, said oppositely disposed fluid portions being in communication with each other through a restricted by-pass, and a pilot valve sleeve slidably mounted around the movable valve member for controlling the pressure of the fluid acting against one of said oppositely disposed fluid portions to govern the operation of the said movable valve member, said pilot valve sleeve being controlled in response to the pressure of the fluid on the entrance side of the major valve.

2. A fluid pressure device comprising, in combination, a body member, a major valve having a movable member slidably mounted in the body member, said movable valve member having two oppositely disposed fluid portions for hydrostatically actuating the movable valve member, said oppositely disposed fluid portions being in communication with each other through a restricted by-pass, a pilot valve sleeve slidably mounted around the movable valve member for controlling the pressure of the fluid acting against one of said oppositely disposed fluid portions to govern the operation of the said movable valve member, said pilot valve being controlled in response to the pressure of the fluid on the entrance side of the major valve, and adjusting means for varying the operation of the pilot valve.

3. A fluid pressure device comprising, in combination, a body member, a major valve having a movable member slidably mounted in the body member, said movable valve member having two oppositely disposed fluid portions for hydrostatically actuating the movable valve member, said oppositely disposed fluid portions being in communication with each other through a restricted by-pass, a pilot valve sleeve slidably mounted around the movable valve member for controlling the pressure of the fluid acting against one of said oppositely disposed fluid portions to govern the operation of the said movable valve member, said pilot valve being controlled in response to the pressure of the fluid on the entrance side of the major valve, and cushioning means for insuring a smooth operation of the pilot valve.

4. A fluid pressure device comprising, in combination, a body member, a major valve having a movable member slidably mounted in the body member, said movable valve member having two oppositely disposed fluid portions for hydrostatically actuating the movable valve member, said oppositely disposed fluid portions being in communication with each other through a restricted by-pass, a pilot valve sleeve slidably mounted around the movable valve member for controlling the pressure of the fluid acting against one of said oppositely disposed fluid portions to govern the

- operation of the said movable valve member, said pilot valve being controlled in response to the pressure of the fluid on the entrance side of the major valve, adjusting means for varying the 5 operation of the pilot valve, and cushioning means for insuring a smooth operation of the pilot valve.
5. A fluid device comprising, in combination, a body member, a major valve member slidably mounted in the body member, said body member 10 having two opposing fluid chambers between which the major valve member may reciprocate incident to changeable fluid pressures in the opposing fluid chambers, said opposing fluid chambers being always in communication with each 15 through a restricted by-pass, and a pilot valve slidably mounted against the major valve member for controlling the fluid pressure in one of the opposing fluid chambers to govern the reciprocal movements of the major valve member, the 20 movements of the said pilot valve being controlled in response to the fluid pressure in the other fluid chamber, adjustable means for varying the operation of the pilot valve, and cushioning means for insuring a smooth operation of the pilot valve.
- 25 6. A fluid device comprising, in combination, a body member, a major valve member slidably mounted in the body member, said body member having two opposing fluid chambers between which the major valve member may reciprocate

incident to changeable fluid pressures in the opposing fluid chambers, said opposing fluid chambers being always in communication with each other through a by-pass, and a pilot valve slidably mounted against the major valve member for 5 controlling the fluid pressure in one of the opposing fluid chambers to govern the reciprocal movements of the major valve member, the movements of the said pilot valve being controlled in response to the fluid pressure in the other fluid 10 chamber.

7. A fluid device comprising, in combination, a body member, a major valve member slidably mounted in the body member, said body member having two opposing fluid chambers between 15 which the major valve member may reciprocate incident to changeable fluid pressures in the opposing fluid chambers, said opposing fluid chambers being always in communication with each other through a by-pass, a pilot valve slidably mounted against the major valve member for controlling the fluid pressure in one of the opposing fluid chambers to govern the reciprocal movements of the major valve member, the movements of the said pilot valve being controlled in 20 response to the fluid pressure in the other fluid chamber, and adjustable means for varying the 25 operation of the pilot valve.

JOHN C. COTNER.
